DESIGN FOR A CONTAINER FOR A SCARF OR SIMILAR ARTICLE

Daniel F. Grotta, New York, N. Y.

Application October 2, 1940, Serial No. 95,599

Term of patent 7 years

To all whom it may concern:

Be it known that I, Daniel F. Grotta, a citizen of the United States, residing in New York city, in the county of New York and State of New York, have invented a new, original, and ornamental Design for a Container for a Scarf or Similar Article, of which the following is a specification, reference being had to the accompanying drawing, forming part thereof.

Fig. 1 is a front elevational view of a container for a scarf or similar article showing my new design;

Fig. 2 is a side perspective view of Fig. 1 on a reduced scale, and

Fig. 3 is an enlarged perspective fragmentary view of the lower portion thereof.

I claim:

The ornamental design for a container for a scarf or similar article, substantially as shown.

DANIEL F. GROTTA.
